Attorney
Harold Orton

UNITED STATES PATENT OFFICE.

GEORGE W. GRANIER, OF RICHMOND HILL, NEW YORK.

QUOIN LOCK.

Application filed May 14, 1921. Serial No. 469,689.

To all whom it may concern:

Be it known that I, GEORGE W. GRANIER, a citizen of the United States, and resident of Richmond Hill, in the county of Queens and State of New York, have invented certain new and useful Improvements in Quoin Locks, of which the following is a specification.

The invention relates in general to an improved form of printer's quoin and particularly relates to a means for locking the wedge members against relative movement when in position in the frame or lock-up.

Various means have been suggested for locking the wedge members of a printer's quoin but they have not been accepted in the trade due largely to the fact that the locking means project beyond the outlines of the frame and thus interfere with the stacking of the frames or "make-ups" or else the locking features do not positively insure against slight creeping of the wedge members.

Accordingly, one of the objects of this invention is to provide a simple form of locking means for positively locking the members in adjusted position so as to defeat any tendency of the wedge members from creeping and which will be of such form as will not interfere with the stacking of the frames and at the same time will not weaken the wedge members nor interfere with the impression while printing.

I attain this invention broadly by pivoting to the upper face of one of the wedge members a flat spring plate, the free end of which is inturned to form a straight key designed to have a snug fit in one of a plurality of closely positioned slots in the other wedge member.

Another object of the invention is to provide a form of locking means which can be readily replaced in case it is damaged and, above all the invention features a construction which can be cheaply manufactured and marketed without adding materially to the present market cost of such devices.

Various other objects and advantages of the invention will be in part obvious from an inspection of the accompanying drawings and in part will be more fully set forth in the following particular description of one form of mechanism embodying my invention, and the invention also consists in certain new and novel features of construc-

tion and combination of parts hereinafter set forth and claimed.

In the accompanying drawings:—

Figure 1 is a plan view of a conventional form of printer's quoin, showing a preferred embodiment of my invention in position thereon and with the locking elements in an inoperative position;

Figure 2 is a view similar to Figure 1 with the locking elements in operative position; and

Figure 3 is a view in side elevation of the showing in Figure 2.

In the following description and in the claims, parts will be identified by specific names for convenience of expression but they are intended to be as generic in their application to similar parts as the art will permit.

In the drawings there is shown two wedging members 10 and 11 having interengaging inclined faces 12 and provided with shifting racks 13 designed to be engaged by a shifting key 14 to move the wedge members longitudinally relative to each other. One side of each of these members is identified for convenience of expression as a top face, 15 and 16 which in such constructions are usually disposed in a single plane. It will be understood that the structure as thus far described is of conventional form and is illustrated simply to show the adaptability of the invention to a conventional form of printer's quoin.

A broad flat spring metal plate 17 is fastened at one end by means of a rivet 18 to the broad end 19 of the member 11. The opposite or free end 20 of the spring plate is bent downwardly at right angles, shown in Figure 3, to form a straight lip 21 constituting a long, rectangular key. The face 15 is provided with a transversely extending straight slot 22 designed to receive one portion of the key as shown in Figure 3. The other face 16 is provided with a series of transversely extending and longitudinally spaced apart slots 23 which slots are preferably positioned relatively close together so that one of the slots 23 will be in alignment with the slot 22 practically in all relative positions of the wedging members. It will be thus seen that the key will fit snugly in the aligned slots and as the key is designed to fit in the slots practically without side play any tendency of the wedging mem-

bers to move longitudinally will be resisted by the straight stiff key 21. It will be understood that even with the wedge members in tight wedging positions it is always possible to spring the containing frame a little further, thus insuring the interfitting of the key in one or the other of the grooves.

With the plate 17 fixed rigidly in position it is possible to move the key simply by springing up the free end of the plate but the connection at 18 may be a pivotal connection in which case the plate will first be raised to clear the key from the slots and then swung out of the way as shown in Figure 1, which arrangement will permit the insertion of the usual shifting key 14.

By means of a device of this character it is possible to securely and permanently lock the wedging members against movement and as the spring 17 is a flat construction there is no material interference with the printing impression nor the stacking of the quoins and even the pivot 18 can be depressed below the slight projection shown in Figure 3. It is possible to shift the plate from the closed to and from the open position shown in Figure 1 without raising this member materially from the plane of the faces and this is of advantage when working within closely confined spaces.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

40 In a device of the class described, I claim:
1. In a printer's quoin, the combination of a pair of wedge-shaped members having interengaging inclined faces, flat top side faces and key-actuated racks constituting a part of means for moving the members relative to each other, a latch pivotally mounted on the broader end of one of said flat top side faces and having a down-turned lip at its free end, the face to which the latch is pivoted provided with a slot for receiving a part of said lip and the other top face provided with a slot for receiving another part of said lip, the engagement of the lip in both

of said slots acting to prevent relative movement in one direction between the members. 55

2. In a printer's quoin, the combination of a pair of wedging members, having top faces, each of said faces provided with an upwardly facing slot extending entirely across the same, said slots adapted to be moved with the members into alignment and a key fixed to the upper side of one of the members and adapted to fit snugly in both of said aligned slots to prevent relative movement in one direction between the 65 members.

3. In a printer's quoin, the combination of a pair of wedging members, one of said members provided with a down-turned lip forming a straight key fixed thereto and 79 the other member provided with a straight slot rectangular in cross section and fashioned to have the key fit snugly therein and thus prevent any relative movement between the members in a direction transversely of 75 the length of the slot.

4. In a device of the class described, the combination of two wedging members, a flat plate pivoted at one end to the upper side of one of the members and provided at its 80 free end with a down turned lip forming a key, the other member provided with a series of slots each of which is designed to have the key fitted therein to prevent relative movement between the members. 85

5. In a device of the class described, the combination of a pair of wedging members, a one piece spring plate secured at one end to one of the members and provided at its free end with down-turned lip forming a 90 key, the other member provided with a slot rectangular in cross-section for receiving the key and thus acting to prevent relative movement between the members.

6. A printer's quoin formed of four members, a pair of wedges, an L-shaped, flat spring locking plate and a fastening means for securing one end of the locking plate to one of the members, the other member provided with recesses for receiving the free 100 end of the spring locking plate. 95

Signed at New York city, in the county of New York and State of New York, this 12th day of May, A. D. 1921.

GEORGE W. GRANIER.
